UNITED STATES PATENT OFFICE.

HERBERT DUUNDERDALE, OF CHICAGO, ILLINOIS, ASSIGNOR TO CHICAGO STANDARD EQUIPMENT COMPANY, OF CHICAGO, ILLINOIS, A CORPORATION OF MAINE.

LADDER.

1,118,404.

Specification of Letters Patent. Patented Nov. 24, 1914.

Application filed April 28, 1914. Serial No. 834,903.

ISSUED

To all whom it may concern:

Be it known that I, HERBERT DUUNDERDALE, a citizen of the United States, residing at Chicago, in the county of Cook and State of Illinois, have invented certain new and useful Improvements in Ladders, of which the following is a specification, reference being had to the accompanying drawings, forming a part hereof.

10 My invention relates generally to ladders, and has reference more particularly to those employed in connection with railway freight cars. One of the objects of my invention is to so construct the stiles and treads of a ladder that they may be easily and quickly assembled in locked relation without the employment of any fastening elements therebetween. Another object of my invention is to provide a ladder which can be assembled and applied to the car at a minimum 20 cost.

A further object of my invention is to produce a ladder which is simple, practical, and rigid in construction; and a ladder capable of withstanding the hardest service usage, and wherein the rungs cannot turn in 25 or become detached from its stiles.

These, together with such other objects as may hereinafter appear, or are incident to 30 my invention, I obtain by means of a construction illustrated in preferred form, in the accompanying drawings, wherein:—

Figures 1 and 2 are front and side elevations, respectively, of a portion of a car showing the application of my improved 35 ladder to both the side and end of the car.

Figure 3 represents an enlarged detail view illustrating the means for attaching the ladder to the car.

40 Figure 4 is a front perspective of a pair of the treads prior to their assemblage in the stiles.

Figure 5 is an enlarged horizontal section taken through the ladder; and Figure 6 is 45 a partial rear elevation of the treads as assembled.

Figures 7 and 8 are views in perspective showing the method of assembling the ladder parts, and the parts as finally assembled 50 in locked relation, respectively.

In carrying out my invention I provide the stiles 9 preferably composed of angle irons, each having inner flanges 9^a and outer lateral flanges 9^b. Both inner flanges 9^a of 55 the stiles are arranged to constitute outer

foot guards, and the lateral flanges 9^b are adapted to be fastened at their ends to the car siding 13 by the strap sections 11 indicated more clearly in Figure 3; the bolts 12 removably connecting the ladder to the strap sections, as in the manner therein shown.

A series of vertically alined holes 14 are formed at intervals in the inner flange 9^a of the stiles to receive and provide a solid bearing for the series of rungs indicated at 65 10 in Figures 1 and 2. A reference to Figures 4, 5 and 6 will show that each of the rungs 10 comprises a tread portion 15 which is provided adjacent its ends with the angular offset portion 16 adapted to engage and rest in the holes 14 formed in the stiles, and whose end portions 17 are bent in a vertical direction away from the said offset portions and slightly incline outwardly to engage the face of the lateral 70 stile flanges 9^b in a locking relation therewith. In this manner the rung 10 is positively locked against any turning movement whatsoever in the holes 14.

This statement of description refers generally to either of the two treads shown in Figure 4, the lower one of which 10^a, however, has preferably each of its inclined end portions 17^a bent in a direction opposite to that of the corresponding bent portions 17^b of the upper rung 10. When the rung 10^a is associated in the stiles with one or more of the rungs 10 to form the ladder, both stiles are consequently locked against relative vertical movement. In other words at 80 a time prior to its application to the car the ladder possesses that degree of rigidity which permits its ready application thereto, and once applied is absolutely rigid in all respects. In practice, the rung 10^a may 85 be alternately arranged with the rungs 10 as indicated in Figure 8, or one or more of either of the rungs 10 or 10^a may be assembled with a series of the other of the rungs in any arrangement as may be considered 90 expedient.

In order to apply the rungs to the stiles, the bent end portions of the rungs 10 and 10^a are passed through the openings 14 in one of the stiles 9 to project beyond the 105 outer flange 9^b, as in the manner shown in Figure 7, said projecting ends being turned so as to have the other end portions terminally register with the openings 14 in the other of the stiles to pass therethrough. 110

The projecting bent ends are then each given a quarter turn to occupy a vertical position so that the other end portions which have passed through the holes 14 are correspondingly brought in place abutting against the outer flange 9^b of the stile, whereupon the first mentioned stile is moved outwardly along the rungs and turned inwardly to the position shown in 10 Figure 8, which illustrates a portion of the complete ladder.

While other commercial rolled sections may be used instead of the angle irons shown, such as a channel iron which use 15 is suggested in Figure 3, I prefer to use the angle irons, for in the event of any desired replacement of a rung, one of the stiles may be quickly uncoupled from its end straps by removing top and bottom 20 bolts 12, which are conveniently placed for this reason, and then moved inwardly along the rungs toward the inner position indicated in Figure 7, so as to permit the removal of the rung and the replacement of 25 another.

From the foregoing it will be obvious that the ladder may be easily and readily applied to the car, and is simple, economical and practical in its construction. Another 30 important feature of my invention lies in the fact that the rungs cannot turn in and cannot come detached from the stiles. Other advantages will be apparent to those skilled in the art.

35 I do not intend to restrict myself to the precise details of construction or to the exact arrangement of the parts as shown, as it is obvious that variations therefrom may be made without departing from the 40 spirit and scope of my invention, as more particularly pointed out in the appended claims.

Having thus described my invention and 45 illustrated its use, what I claim as new and desire to secure by Letters Patent, is the following:—

50 1. A ladder comprising stiles and a plurality of detachable rungs, each stile having divergent flanges and formed with a hole in one of its flanges, said rungs having hole 55 engaging portions and oppositely bent end portions each inclining outwardly from said hole engaging portions substantially in a vertical direction to abut the other of the flanges at points respectively above and below the said holes, substantially as and for the purposes set forth.

55 2. A safety ladder comprising angle bar stiles and a plurality of rungs, each stile 60 having inner and outer flanges and formed

with a hole in its inner flange, and each rung comprising a tread having offset hole 65 engaging portions and oppositely bent end portions inclining outwardly from said offset portions substantially in a vertical direction to have an abutting locked relation with the inner face of the outer flange at points respectively above and below the medium line of the tread.

3. In a safety ladder, the combination of 70 a pair of stiles and a plurality of rungs therefor, each of said stiles having inner and outer divergent flanges and formed with holes in its inner flange, one of said rungs being provided with hole-engaging 75 portions and oppositely bent end portions disposed in an abutting relation with the inner faces of the outer flanges at each side of the ladder, and an adjacently positioned rung adapted to engage another pair of 80 holes and having an end portion locking with the outer flange at one side of the ladder, said end portion being oppositely bent with respect to the adjacent end portion of the first mentioned rung to lock the 85 stiles against relative movement in the plane of the ladder.

4. In a safety ladder, the combination of 90 a pair of angle bar stiles each having holes formed in one of its divergent flanges and a pair of rungs having offset portions 95 engaging in said holes, each rung having oppositely bent end portions extending angularly from said offset portions to engage the sides of the stiles, said end portions at one side of the ladder being bent inwardly 100 toward each other and outwardly away from each other at the other side of the ladder to lock the rungs.

5. A ladder comprising stiles and a plurality of rungs, adjacent ends of said rungs at one side of the ladder having offset hole 105 engaging portions and oppositely bent end portions inclining outwardly from said offset portions, and one of the stiles having divergent flanges and formed with vertically aligned holes in one of its flanges through which the said offset and bent end portion are initially passed, the other flange of the stile being turnable inwardly on the 110 offset portions to abut the said oppositely bent end portions to lock the rungs, substantially as described.

In testimony whereof I have hereunto signed my name in the presence of the two 115 subscribed witnesses.

HERBERT DUNDERDALE.
